UNITED STATES PATENT OFFICE.

EDWIN F. PORTER AND WALTER R. WHITING, OF BOSTON, MASSACHUSETTS, ASSIGNORS TO AMERICAN ROTARY ENGINE COMPANY, OF BOSTON, MASSACHUSETTS, A CORPORATION OF MAINE.

GAS-ENGINE.

No. 810,347.

Specification of Letters Patent.

Patented Jan. 16, 1906.

Application filed March 16, 1905. Serial No. 250,368.

To all whom it may concern:

Be it known that we, EDWIN F. PORTER and WALTER R. WHITING, of Boston, in the county of Suffolk and State of Massachusetts, 5 have invented certain new and useful Improvements in Gas-Engines, of which the following is a specification.

This invention has relation to "gas-engines," so called, of the type illustrated in 10 the copending application of Porter and Whiting, Serial No. 37,615, filed November 24, 1901. In the engine set forth in said application the piston is connected to two oppositely-rotating crank-shafts by separate pitmen, provision being made for gearing the said crank-shafts together to insure their synchronous rotation in opposite directions. In the construction of such engines it has been found that there is a tendency of the pitmen to twist the piston and cause it to bind in the cylinder. This is sometimes due to the play between the gears which connect the crank-shafts, to the wearing away of the crank-pins or pitmen, or to 20 inequalities in the length of the two pitmen. According to this present invention, however, we provide a loose connection between the block to which the pitmen are pivoted and the piston to compensate for inequalities 25 in the length of the pitmen and to prevent the piston from binding in the cylinder.

On the drawings, Figure 1 represents, partially in section, a gas-engine equipped with our improvements. Fig. 2 shows in detail 35 the loose connection between the pitman-block and the piston. Fig. 3 represents a somewhat different embodiment of the invention.

On the drawings the cylinder is indicated 40 at *a* and the piston at *b*.

The two crank-shafts are indicated at *c c*, and they are geared together by suitable gears *d d*. As set forth in the application hereinbefore referred to, the two crank-shafts 45 are provided with momentum-wheels, the two wheels, however, being mounted upon the opposite ends of the shafts to which they are attached.

e e indicate pitmen, which are preferably 50 of the same length and which are straight, as shown. Each pitman is pivoted upon a stud *f*, passed through the ears *g'* of a pitman-block *g*. The two studs *f f* are parallel, as

shown in Fig. 1. The pitman-block is pivotally connected to the cylinder by a pintle 55 *g*. The piston is preferably hollow, as shown, and the pitman-block is located therein, being adapted to slide to a limited extent longitudinally upon the pintle *g*, upon which it is pivoted. The extent to which the pitman-block is adapted to move, however, is limited by annular flanges *b'* formed on the interior or walls of the piston.

By virtue of this construction there is a universal movement between the pitman and the piston, and consequently there is no possibility of twisting or forcing the piston out of true with the interior walls of the cylinder or causing it to bind or become cramped therein.

It is evident that in lieu of the particular arrangement shown in Figs. 1 and 2 the construction shown in Fig. 3 may be employed, in which the pintle *h*, which corresponds to that at *g*, may be located in parallelism with 75 the studs *f f* of the pitman-block.

It is desirable to employ the two separate studs *f f* in connection with the straight pitmen *e* rather than to connect the two pitmen with the pitman-block by a single stud, for 80 in that event the pitmen would have to be offset and under the strains experienced in an engine of this character would be liable to become bent or broken or at least to yield under the strain.

Having thus explained the nature of the invention and described a way of constructing and using the same, although without attempting to set forth all of the forms in which it may be made or all of the modes of its use, 90 we declare that what we claim is—

1. In combination with a cylinder, a piston, two oppositely-rotating crank-shafts, and two pitmen connected to said crank-shafts, of means interposed between said 95 pitmen and piston for loosely connecting the former to the latter to provide lost motion between the said parts.

2. The combination with a cylinder, a piston, two oppositely-rotating crank-shafts, a 100 pitman connected to each crank-shaft, a pitman-block having separate studs or pivots for the pitman, and means for loosely connecting said pitman-block to said piston.

3. The combination with a cylinder, a piston, oppositely-rotating crank-shafts, a sep- 105

- arate pitman for each crank-shaft, a pitman-block having separate studs or pivots for each pitman, and a pintle loosely connecting said pitman-block with said piston.
5. 4. The combination with a cylinder, a piston, oppositely-rotating crank-shafts, pitmen connecting said crank-shafts to a member which is loosely mounted on and adapted to change its relative position with said piston.
10. 5. The combination with a cylinder, a piston, oppositely-rotating crank-shafts, pitmen connecting said crank-shafts to a member

which is loosely mounted on and adapted to change its relative position with said piston and accommodate itself to any unequal motion of said pitmen. 15

In testimony whereof we have affixed our signatures in presence of two witnesses.

EDWIN F. PORTER.
WALTER R. WHITING.
